UNITED STATES PATENT OFFICE.

ROY F. ENSIGN, OF SOUTH PASADENA, CALIFORNIA, ASSIGNOR TO ENSIGN CARBURETER COMPANY, OF LOS ANGELES, CALIFORNIA, A CORPORATION OF CALIFORNIA.

OILING DEVICE FOR INTERNAL-COMBUSTION ENGINES.

Application filed December 12, 1925. Serial No. 74,989.

The majority of present day internal combustion engines lubricate the piston rings with oil splashed from the crank thrown in the crank case. In most instances when engines of this type are operating at heavy loads this method of lubrication does not properly lubricate the upper rings of the pistons, and such lack of proper lubrication results in wear of the cylinders and piston rings and consequent loss of power from friction.

5 An object of this invention is to provide novel means whereby oil is supplied to the engine pistons and cylinders when the engine is operating at a large per cent of full load to thereby properly lubricate such working parts at such motor loads.

Another object is to construct a novel device that will accomplish this result and 15 which may be attached to engines of present construction.

Simplicity of construction and elimination of all moving parts in my device of this character are other objects.

25 A feature of the invention is in the provision of novel means whereby oil is introduced into the upper portion of the cylinders through the intake manifold only when the engine is operating at loads over say 30 about half load.

A further object is to construct a novel device of this character whereby the suction in the intake manifold is utilized during certain engine loads to deliver oil from the 35 device to the intake manifold and to divert from the passage into the intake manifold, during low engine loads, oil introduced into my device from which it returns to the engine.

40 I will describe my device as applied to internal combustion engines in which the oil pressure in the oil feed lines is maintained more or less uniform due to the interposition of a relief valve. However, my device may 45 be applied with equally as good results, to engines in which the oil pressure varies with the speed of the motor. The only change being in the manner of adjustment which will be apparent to those skilled in the art.

50 Other objects, advantages and features of invention may appear from the accompanying drawing, the subjoined detail description and the appended claims,

The accompanying drawing illustrates the invention in a form at present deemed preferable.

55 Figure 1 is an axial sectional view of my device attached to the manifold of an internal combustion engine a fragment of which is shown. Portions are broken away 60 to show interior construction.

Fig. 2 is an elevation of my device detached from the engine and looking from the left of Fig. 1.

65 The internal combustion engine 1 comprises the usual intake manifold 2, carbureter 3, and crank case 4 to which the oil pump 5 is connected at any suitable point by means of pipe 6. A pipe 7 leading from the pump 5 conducts oil to the usual engine 70 bearings in a manner well known in the art. The foregoing elements being well known and of any standard construction will not be described in detail.

75 My invention includes an oiling device comprising a casting 8 which has an oil receiving chamber 9 therein adapted to receive oil from the crank case through a branch pipe 10 which is connected to the pipe 7 and opens into the upper end of said chamber 9 80 through an inlet 11 in the form of a reduced orifice that is under control of a needle valve 12, which screws into the casting 8 in line with said orifice.

85 The lower end of the chamber 9 is provided with a nozzle 13 which is in alignment with, and from which at certain stages of engine operation oil will be discharged into, an oil return pipe 14 that is connected to any suitable point in the crank case so that 90 oil delivered thereto from nozzle 13 will be returned to the supply in the crank case.

95 The pipe 14 is preferably connected to the crank case below the oil level therein so that the passage through pipe 14 will be sealed by oil from the crank case. The purpose of this seal will be more fully hereinafter explained. It is apparent that the seal may be formed by a U-shaped trap formed in the pipe and which trap is then filled with oil.

100 A stand pipe 15 is threaded into the lower end of the casting 8 in a boss and has a reduced portion 17 that forms with bore 18 an annular chamber 19. The upper end of the reduced portion encircles the nozzle 13 105 and is spaced therefrom a slight distance to

provide for communication between the chamber 18 and the bore of stand pipe 15 and which bore may be said to be an extension of pipe 14.

5 A drip chamber 20 is formed by a glass tube 20' which is secured to body 16 by screws 21 and cover plate 22. Gaskets 23 form a liquid tight joint between the tube 20'; cover plate 22 and body 16 to prevent 10 leakage of oil from said chamber 20.

The chamber 20 is open to the atmosphere through an air vent 23 and is connected to the annular chamber 19 through a nozzle 24.

15 A drip pipe 25 is visible through tube 20' and connects chamber 9 above the nozzle 13 with the chamber 20. The drip pipe 25 terminates above the oil level 26 in chamber 20 and at approximately the same height as the lower end of nozzle 13.

20 My device may be attached or installed at any convenient place relative to the engine but is shown as being supported by a pipe nipple 27 threaded into the intake manifold 2 and casting 8. The pipe 27 opens into the 25 manifold 2 and connects the same with the annular chamber 19 through a reduced orifice 28.

In operation with the engine operating at any load the pump 5 will deliver under a 30 certain degree of pressure and under control of valve 12 to the oil receiving chamber 9, oil from the crank case 4.

The oil delivered to the oil receiving chamber 9 will fall by gravity to the lower 35 end thereof and at loads below say about half load is drawn through nozzle 13 into pipe 14 by the suction head applied in said pipe from the variable depression in intake manifold 2 through annular chamber 19 by 40 way of orifice 28 which is made only sufficiently large to allow passage of the necessary amount of oil to lubricate the piston rings as the orifice 28 is an air lead on the manifold 2. The depression in manifold 2 45 varies widely from no load to full load and is greatest at no load.

Oil passing through nozzle 13 will fall by gravity through the stand pipe 15 and into pipe 14 through which it will be returned to 50 the crank case.

The suction head applied in chamber 19 is communicated to the pipe 14 through the small space between the reduced end 17 of stand pipe 15 and nozzle 13, and raises the 55 oil in pipe 14 from the normal level 29 to a point say about at 30.

As the load on the engine is increased the suction head on orifice 28 will decrease practically to atmospheric pressure when full 60 load is reached and a very small percent of oil entering chamber 9 will pass through the nozzle 13 and the flow will then be through drip pipe 25 into chamber 20 from which the oil flows through nozzle 24 into annular 65 chamber 19 and thence through orifice 28

into the manifold 2 from which it is carried to the engine cylinders by the combustible charge of fuel and air passing therethrough.

The amount of air flowing through orifice 28 will not appreciably decrease until about 70 half load is reached and until such time oil will continue to flow from nozzle 13 and then gradually decrease as the load increases. The minimum flow through nozzle 13 will occur when the engine is operating at full 75 load.

The nozzle 24 is of such size that the friction of air and oil passing through it to orifice 28 will create in chamber 19 the desired depression. 80

For adjustment it is preferable to first open the needle valve 12 with the engine operating at no load until oil drips from pipe 25. This may be easily visualized through the translucent tube 20'. The valve 12 is 85 then closed to a position where the oil just stops flowing from pipe 25. The device is then adjusted ready for use provided the various nozzles have been properly proportioned to adapt the device to the particular 90 type or make of engine to which the device is attached.

I claim:

1. In combination with an internal combustion engine having an intake manifold, 95 a crank case; and means adapted to pump oil from said crank case to bearings of said engine; a body having an oil receiving chamber connected to receive oil from said pump means; a pipe connected to conduct oil from the chamber to said crank case; a drip chamber connected to said oil receiving chamber and open to the atmosphere; and means connecting said drip chamber to said intake manifold. 105

2. An attachment of the character described for internal combustion engines comprising a body provided with an oil receiving chamber having a valve controlled inlet; a drip chamber connected to said oil receiving chamber and open to the atmosphere; a nozzle opening from the lower end of said oil receiving chamber; a stand pipe threaded to said body and adapted to receive oil from said nozzle; a chamber 110 around said stand pipe; another nozzle connecting the last mentioned chamber with said drip chamber; and means to connect the chamber around the stand pipe with the intake manifold of an internal combustion engine. 115

3. An oiling device for internal combustion engines comprising an oil receiving chamber having an inlet and a nozzle; a drip chamber; means connecting said receiving chamber and said drip chamber; a pipe to receive oil from said nozzle and having a liquid seal therein; and means connected to deliver oil from said drip chamber to the intake manifold of an engine during 120 125 130

engine loads above about one half and to apply a depression on said nozzle at engine loads below about one half.

4. In combination with an internal combustion engine having an intake manifold, a crank case; and means adapted to pump oil from said crank case to bearings of said engine, a body having an oil receiving chamber connected to receive oil from said pump means, means to adjust the flow from said pump means to said chamber, a pipe connected to conduct oil from the chamber to said crank case, a drip chamber connected to said oil receiving chamber and open to the atmosphere; and means connecting said drip chamber to said intake manifold.
5. In combination with an internal combustion engine having an intake manifold, a crank case; and means adapted to pump oil from said crank case to bearings of said engine; a body having an oil receiving chamber connected to receive oil from said pump means; a pipe connected to conduct oil from the chamber to said crank case; a drip chamber connected to said oil receiving chamber and open to the atmosphere; and means connecting said drip chamber to said intake manifold.
6. In combination with an internal com-
- bustion engine having an intake manifold, a crank case; and means adapted to pump oil from said crank case to bearings of said engine; a body having an oil receiving chamber connected to receive oil from said pump means; a pipe connected to conduct oil from the chamber to said crank case; a drip chamber connected to said oil receiving chamber and open to the atmosphere; and means connecting said drip chamber to said intake manifold, said pipe extending into and being open to said annular chamber.
7. In combination with an internal combustion engine having an intake manifold, a crank case; and means adapted to pump oil from said crank case to bearings of said engine; a body having an oil receiving chamber connected to receive oil from said pump means; a pipe connected to conduct oil from the chamber to said crank case; a drip chamber connected to said oil receiving chamber and open to the atmosphere; and means connecting said drip chamber to said pipe to said intake manifold.

In testimony whereof, I have hereunto set my hand at Los Angeles, California, this 5th day of December, 1925.

ROY F. ENSIGN.
